UNITED STATES PATENT OFFICE.

PETER L. WILBUR, OF TUCKAHOE, NEW YORK, ASSIGNOR TO AMPYR MANUFACTURING COMPANY, INC., OF NEW YORK, N. Y., A CORPORATION OF NEW YORK.

SUPPORTING BRACKET.

Application filed August 11, 1920. Serial No. 402,923.

To all whom it may concern:

Be it known that I, PETER L. WILBUR, a citizen of the United States, and a resident of Tuckahoe, in the county of Westchester 5 and State of New York, have invented certain new and useful Improvements in Supporting Brackets, of which the following is a specification.

This invention relates to brackets to which 10 articles may be detachably connected to support the same by the brackets, as from a wall or the like, and it is the object of the invention to provide an improved bracket for this purpose which is novel, simple and cheap 15 in construction and efficient in use, and to means to be attached to the article to co-operate with the bracket to support the article from the bracket.

While I have shown in the drawing a 20 bracket which is particularly adapted for supporting a fire extinguisher of a syringe type in a vertical position from a wall or the like, it is to be understood that the invention is not limited to the detachable supporting 25 of a fire extinguisher and that various articles may be arranged to be detachably connected to and supported by the bracket.

In the drawing accompanying and forming 30 a part of the specification, Figure 1 is a front elevation of a fire extinguisher supported by the bracket shown in dotted lines.

Figure 2 is a sectional side elevation of the 35 bracket fixed to a support, as a wall, and showing the manner of detachably supporting an article thereby.

Figure 3 is a view looking at the top of Figure 1, partly in section, to show the manner of adapting the means to a container of a fire extinguisher and the manner in which 40 said means cooperates with the bracket to detachably connect the extinguisher to the bracket.

Figure 4 is a perspective view of the bracket.

45 Figure 5 is an enlarged sectional detailed view to show the manner of connecting an article to the bracket and the means to releasably lock the article to the bracket;

Figure 6 is an end elevation of a detail 50 showing a modified form of the bracket.

Similar characters of reference designate like parts throughout the different views of the drawing.

The embodiment of the invention shown 55 in the drawing comprises a plate of sheet

metal, designated in a general way by 7, this plate being bent to form outwardly bulging portions 8, 9 with the extremities of the plate and the portion between the bulged portions extending substantially in the same plane 60 and adapted to lie contiguous to the support upon which the bracket is to be mounted such as a wall as shown at 10, and such portions provided with perforations 11 for the engagement of securing means, as screws 12. 65 The bulged portions 8, 9 are provided with openings 13, the openings being of greater width at one end portion than at the other end as shown.

To detachably connect an article to and 70 support the same from the bracket, the article, shown in the present instance as a fire extinguisher, is provided with studs or knobs 14 in equidistant spaced relation to the openings 13 in the bracket, fastened to the 75 container of the extinguisher or other article to be supported by the bracket, in a suitable manner and shown as riveted to the container as at 15, Figure 3.

The cross sectional dimensions of the studs 80 are such as to permit of the passage of the heads through the large portion of the openings 13, and the reduced portion below the heads to engage and have free movement 85 in the portion of the openings of less width 85 with the heads to engage at the rear of the lateral walls of the reduced portion of the openings thereby preventing the studs from being pulled out from the front of the openings by the weight of the article. To prevent 90 vibration or chattering of the article in the support, the portion of the studs to engage the reduced portion of the openings 13 in the bracket is in the form of an annular recess which is of a width substantially the 95 same as the thickness of the metal of the bracket, the opposite walls of this recess forming shoulders engaging opposite faces of the bracket and thereby firmly holding the article supported by the bracket against forward or backward movement.

To releasably lock the article to the bracket to prevent accidental dislodgement of the studs from the bracket openings, as by a sudden jar or otherwise, a resilient 105 locking member in the form of a spring detent 16 is fixed at one end in the rear of the bulged portion 8 with the free end provided with a projection 17 and extending to a point above the portion of the opening of 110

reduced width in position to engage over the head of the stud when the stud is engaging said portion of the opening. While this locking member will prevent the accidental 5 movement of the stud in the openings as by a sudden jar or the like, the article may be readily detached from the bracket.

To steady an article supported by the bracket against lateral movement fingers 18 10 projecting laterally in opposite directions and slightly forward from the bracket are arranged to engage opposite portions of the article. These fingers are preferably located at the base of the bulged portion 8 and may 15 be constructed integral with the material of the bracket. However, this is not essential as they may be constructed separate from the plate of the bracket and secured thereto, and in Figure 6 I have shown such an arrangement, the fingers being formed of and 20 consisting of a separate member fastened to the bracket by the means for fastening the detent 16 thereto.

Having thus described my invention I 25 claim:

1. In a bracket, a plate formed with

bulged portions with the extremities of the plate and the portion between the bulged portions extending in the same plane, openings in the bulged portions having portions 30 of different widths, fingers projecting laterally and forward of the plate, and a detent arranged in the rear of the opening in the bracket for the purpose specified.

2. The combinations with an article having headed studs, of a supporting bracket for the article comprising a plate having bulged portions with openings of different widths for the passage of headed studs and the engagement of the studs, fingers projecting laterally and forward of the plate to embrace opposite portions of the article supported by the bracket, and a locking member connected to the rear face of a bulged portion of the plate, and co-operating with the 40 stud, to releasably retain the studs in the opening.

Signed at New York city, in the county and State of New York, this 13th day of July, 1920.

PETER L. WILBUR.
